UNITED STATES PATENT OFFICE.

GEORGE E. NEUBERTH, OF NEWARK, NEW JERSEY.

CASTER-SOCKET.

1,128,623.

Specification of Letters Patent. Patented Feb. 16, 1915.

Application filed June 13, 1914. Serial No. 844,862.

To all whom it may concern:

Be it known that I, GEORGE E. NEUBERTH, a citizen of the United States, and a resident of Newark, county of Essex, and State of New Jersey, have invented certain new and useful Improvements in Caster-Sockets, of which the following is a specification.

This invention relates to an improved socket for casters and is adapted for use 10 with any form of caster, although it is particularly adapted for the standard type, the socket being of the kind that is used on hollow posts of beds and the like, the post or tubing being provided with a socket which 15 is permanently affixed to the tubing, the pintle member being detachable from the socket.

The invention relates to a socket of this kind which is inserted in a tube and is then 20 manipulated so that it is permanently attached to the tubing, this being accomplished by the manipulation of an expandable gripping device which is arranged on the socket so that when in place it is within 25 the tubing or post in which the socket is secured. The socket is adapted to be secured to posts of different interior diameters, the same socket answering for different forms and sizes of posts.

30 In the ordinary spring type of socket, which is compressed as it enters the posts, the spring members being normally farther apart than the interior diameter of the post, a different socket must be made for each 35 different form of post. Furthermore, posts are very often of the same diameter on the outside, but of a different diameter on the inside, since different gages or thicknesses of material are used in the different posts 40 according to the quality of the work and the size of the bed or other piece of furniture of which the post is a part. This necessitates the carrying by a bed manufacturer of a great many different sizes of sockets for 45 the different interior diameters of the posts. With my invention this objection is overcome as the socket is normally smaller than any of the interior diameters of the posts, of course within a certain range of diameters, and the socket is adapted to be expanded 50 within these different sizes of posts so as to fit any of them, and it is therefore necessary to carry only one form of socket which can be fitted into any of the posts 55 within a certain range of diameters.

The invention is further designed to pro-

vide a socket which can be used both in round or square tubing, and is formed so that it is adapted to be secured against any accidental removal. The insertion and se- 60 curing of the socket is simple, since the socket is constructed so that the expandable member is accessible so that a tool can be employed to force the gripping device to its gripping position by a push or blow 65 against the movable or expandable member of the gripping device.

The invention is also designed to provide a socket which engages the post at the bottom and which has a gripping device to en- 70 gage the post at a considerable distance above the bottom of the post so that the socket is held in line with the post. In other words it is securely fastened in place and does not tilt when the weight of the piece 75 of furniture comes on the caster or the furniture is pushed to move it along the floor. This is an improvement over the old type 80 of caster socket which engages the post only at the bottom or engages it loosely at the top of the socket, since these forms are subject to tilting, and the caster pintle lies at an angle in the post and the turning of the caster is difficult. My improved socket overcomes this defect and the pintle of the caster is 85 held in the socket substantially in line with the post of the piece of furniture.

The invention is further designed to pro- 90 vide a socket which is made of few parts, the parts being all made of sheet metal, al- though other material can be used so long as the parts can be quickly assembled.

The invention is illustrated in the accom- 95 panying drawing in which one embodiment of the invention is shown which, however, will be understood to be susceptible to slight modifications and changes without depart- ing from the scope of the invention.

In the drawing, Figure 1 is a side view of the socket illustrated as being arranged 100 within the bottom of a post or tube, the tube being shown in section. Fig. 2 is a similar view with the socket shown in section and a pintle member illustrated in place, the pintle member and the roller be- 105 ing shown by dotted lines. Fig. 3 is a top view of the device shown in Fig. 2. Fig. 4 is a section on line 4-4 in Fig. 1, and Fig. 5 is a cross-section taken on the line 5-5 in Fig. 3.

In the drawing the post or tube 10, which may be a post of any article of furniture,

such as a bed, is hollow, these posts being usually made of sheet metal, and while they are of the same diameter on the outside, different thicknesses of material are used so that different posts will have different interior diameters. The socket is adapted to fit within this post and is provided with a pintle-receiving means and also means for fastening it within the post or tube, and also with means for limiting its entrance into the tube, this being usually by means of a stop that engages the bottom end of the tube. The disk for limiting this entrance of the socket consists of a disk or plate 11 which bears against the bottom edge of the post, and while it may be made flat, it is usually provided with corrugations to stiffen it and also to provide points on which the caster bears so as to minimize the area of contact with the caster and thus cut down the friction so that the caster can be swiveled in the socket and will turn easily therein when a weight is put on the caster. Such corrugations are shown at 12 and 13. Secured to the disk is a pintle-engaging portion, this being usually in the form of a tube 14 which tapers toward the top and has slots 15 so as to split the top end and give it more resiliency. The tube 14 is usually secured to the disk by crimping it as at 16 to hold it securely in place.

The pintle member 17 may be of any type, but I prefer to use the standard type of member which consists of a horn 18 which has a pintle 19 which projects therefrom, the pintle having its upper end bulged or enlarged as at 20 so that when the pintle is inserted in the tube 14 the split top portion is spread by the head 20 and snaps in underneath the head when the pintle is pushed all the way in, and thus holds the pintle against accidental removal so that it will not fall out when the post is raised so that the pintle is elevated above the floor. The pintle, however, can be removed by a strong pull or a jerk.

On the disk is mounted a suitable gripping device for engaging the inner walls or faces of the post 10, this gripping device being normally smaller than the inside diameter of the post, but is adapted to be expanded when the socket is in place so that the socket is rigidly held within the post and is permanently secured therein. In the type of device shown in the drawing the gripping device consists of a member 21 which is fastened to the disk, the member 21 being made arch-shaped with the side walls 22 and 23 and the top 24. The side walls have flaps 25 which project down through slots 26 in the disk 11 and are turned over to fasten the member in fixed position on the flange. On one end of the arch-shaped member, which for convenience I shall call in this specification the back

end, the edges of the sides 22 and 23 are provided with inclined guides 27 which incline downward and inward and are arranged with an outward flare as shown particularly in Fig. 4, this outwardly flared portion 28 acting as a guide-way for the movable member of the gripping device. The movable member 29 is usually made of sheet metal and on its side edges it has inwardly turned flanges 30 which engage the guides 28 of the fixed member so that a dove-tailed connecting portion is formed which prevents the separation of the parts on account of the flare of the guides 28 and the converging of the flanges 30. At the bottom of the movable member 29 is an inwardly turned plate or anvil 31 which forms an abutment. This abutment engages at the back edge 32 of the top 24 and thus limits the upward sliding of the movable member 29 and prevents its loss when the socket is handled before it is inserted in the post 10. The disk is provided with a perforation 33 which is so disposed that it gives access to the movable member, which will be described hereinafter.

When the socket is to be placed in the post 10 the movable member is in a low position as shown in Fig. 1 so that the distance between the back edge of the member 29 and the front edges of the arch-shaped member is as small as possible so as to make the entrance of the socket into the post easy. When the socket is in this position a suitable tool or nail 34 is inserted through the hole 33 and by a steady push or by tapping it with a hammer, the movable member 29 is forced up along the guides 27 and is forced at the same time outward so as to expand the gripping device and cause the two members 21 and 29 to tightly engage the inner wall of the post 10. It will be understood that the outer faces of the arch-shaped member and the member 29 can be of any suitable conformation, but in the form shown they are square so that the corners 35 engage the inner face of the post 10 and securely clamp the socket in position. It will be readily seen that this form of socket can also be used in square tubes or rectangular tubes of different kinds, and when expanded will tightly fit within the tubes and be held against removal. When the socket is in place the pintle can be inserted in the socket and held as above described. The top 24 of the arch-shaped member is provided with a suitable opening 36 through which the top of the pintle 19 can pass, the tube 14 being made of a length to project slightly above the arch-shaped member.

It will be seen from the above description that the socket when placed in the post engages the post at the bottom and also has its gripping device engage the inside of the

post at the top of the socket so that the post is engaged at vertically separated points. This construction, which permits this form of fastening of the socket, holds the socket 5 so that the pintle-engaging part is normally in line with the post 10, in the form shown this being the tube 14 which is held against tilting, and the post 10 is held vertically when the weight of the furniture rests on 10 the caster and when the furniture is moved laterally along the floor. This permits the easy turning of the caster and is an important feature of this invention.

The socket above described is of very simple construction and is easily assembled, it being necessary only to slide the movable member 29 onto its guides, and after placing the member 21 on the disk 11 the fingers 25 are turned over to hold the parts in place.

20 Having thus described my invention, what I claim is:—

1. A caster socket having a manually operated device so disposed that it is expandible to its gripping position.

25 2. A caster socket having expandible means on said socket, the socket being constructed to permit access to said means when the socket is in a post.

3. A caster socket comprising a fixed 30 member, and a member slidable on said fixed member to vary the width of the socket.

4. A caster socket comprising a fixed member, and a member secured to and slideable on the fixed member in an oblique direction.

35 5. A caster socket comprising a fixed member with inclined guides, and a movable member secured to and slideable in said guides.

40 6. A caster socket comprising a fixed member with guides that are inclined, the guides projecting outwardly, a movable member, and inwardly projecting inclined ribs slideable on the guides.

7. A caster socket comprising a disk, a fixed member, a movable member, the disk having an opening therein, and an abutment on the movable member and disposed so that it can be operated through the opening in the disk.

50 8. A caster socket comprising a fixed member, a movable member mounted on the fixed member so that it can slide thereon in an oblique direction, and an abutment on the movable member.

55 9. A caster socket comprising a disk, an arch-shaped member on the disk, the back edges of the member being inclined to form guides, a substantially flat movable member with its side edges provided with flanges inclined to fit the guides of the first member, the movable member being bent over at the bottom to form an abutment, the disk having an opening so that a tool can be forced against the abutment.

60 10. A caster socket comprising a disk at the bottom of the socket, pintle engaging means projecting vertically from the disk, and an outwardly operable gripping device on the socket, said gripping device being 70 located at the top of the socket, whereby the lower and upper post-engaging parts are vertically separated.

65 11. A caster socket comprising a disk, and a gripping device projecting vertically from the disk, said gripping device being adapted to be expanded to grip the inside of a post, the gripping device being arranged at a point that is vertically separated from the disk.

75 In testimony that I claim the foregoing, I have hereto set my hand, this 12th day of June, 1914.

GEORGE E. NEUBERTH.
